CLAIM

The ornamental design for a speaker, as shown and described.

DESCRIPTION

FIG. 1 is a top, front perspective view of a speaker showing our new design.

FIG. 2 is a top, back perspective view thereof.

FIG. 3 is a front elevational view thereof.

FIG. 4 is a back elevational view thereof.

FIG. 5 is a top plan view thereof.

FIG. 6 is a bottom plan view thereof.

FIG. 7 is a side elevational view thereof; and,

FIG. 8 is an opposite side elevational view thereof.

The broken lines in the figures illustrate the portions of the design that form no part of the claimed design.

1 Claim, 4 Drawing Sheets(56)
